UNITED STATES PATENT OFFICE.

FRANK J. WILLS, OF WINCHESTER, MASSACHUSETTS, ASSIGNOR OF ONE-HALF TO GEORGE FRANCIS TOPLIFF, OF BOSTON, MASSACHUSETTS.

TICKET PRINTING AND AUDITING MACHINE.

No. 820,277.

Specification of Letters Patent.

Patented May 8, 1906.

Application filed January 14, 1898. Serial No. 666,661.

To all whom it may concern:

Be it known that I, FRANK J. WILLS, of Winchester, in the county of Middlesex and State of Massachusetts, have invented certain new and useful Improvements in Ticket Printing and Auditing Machines, of which the following is a specification.

This invention has relation to machines for printing tickets for use on railways and for analogous purposes.

The object of the invention may be briefly stated to be the provision of a machine of the class mentioned by means of which the ticket agent at any one station in a railway system may print and deliver a ticket bearing on its face the name of any other station in the same system and which will automatically record upon a record-sheet the number of each ticket, the destination thereof, together with the total amount the agent should receive for all tickets sold, whereby the price of each ticket may be ascertained.

Another object of the invention is to provide a machine with means whereby the record of the tickets sold may be so arranged that the auditor or the official whose duty it is to collect and examine the tally or record sheets may determine at a glance the number of tickets sold to any particular station.

Still another object of the invention is to equip the machine with certain features of improvement, all of which will be explained in detail in the following specification, illustrated upon the drawings, and set forth more particularly in the appended claims.

Reference is to be had to the accompanying drawings, and to the letters and figures marked thereon, forming a part of this specification, the same letters designating the same parts or features, as the case may be, wherever they occur.

Of the drawings, Figure 1 is a front elevation of the machine with the casing removed. Fig. 2 represents a plan view of the same. Fig. 3 represents a vertical longitudinal section on the line 3-3 of Fig. 2. Fig. 4 represents a transverse section through the machine on the line 4-4 of Fig. 1. Fig. 5 represents an end elevation of a machine, partially in section. Fig. 6 represents an elevation of the opposite end. Fig. 7 represents a plan view, partially in section, the parts being enlarged. Fig. 8 represents a vertical sectional view taken through the machine in such way

as to illustrate the prime power device. Fig. 9 represents in detail the checking mechanism for the power devices. Fig. 10 represents in detail a portion of the prime power devices. Fig. 11 represents in vertical longitudinal view that portion of the machine containing the printing mechanism. Figs. 12, 13, 14, and 15 represent in detail portions of the printing mechanism. Fig. 15^a represents in perspective view the tension device for the ticket-strips. Fig. 16 represents the means for temporarily connecting the key reservoir or carrier with a traveling belt actuated by the power devices. Figs. 17 and 18 represent in detail a portion of the mechanism operated by keys for coacting with the type-reservoir carrier. Figs. 19, 20, 21, 22, 23, 24, 25, 26, 27, 28, 29, 30, 31, and 32 represent in detail the auditing mechanism. Fig. 33 represents in detail a gearing for the printing mechanism. Fig. 34 illustrates in perspective view the power checking and releasing mechanism. Figs. 35, 36, and 37 illustrate in detail portions of the carrier for the type-bar. Fig. 38 illustrates the stops for the ticket-strip tension and withdrawing device. Fig. 38^a shows the end of one of the type-bars. Fig. 39 shows the record-sheet. Fig. 40 represents one form of type set upon the printing-cylinder. Fig. 41 shows a ticket as it is delivered from the machine with the lower line printed by the movable type which is automatically set in the printing-cylinder.

Now referring to the drawings, which represent one embodiment of the invention which I have selected for the purpose of illustration, and to the details of construction, of which it will be understood I am not limited, the machine thereon shown is provided with a casing which incloses all of the working parts thereof, with the exception of those keys or parts which must be manipulated by the ticket agent at the railway-office. This casing may be constructed of any suitable material and may be of any conformation or shape best adapted to inclose and protect the various mechanisms forming a part of the entire machine, being provided with suitable doors, through which access may be had to various parts of the mechanism.

The machine as a whole consists of several parts, which may be briefly described, as follows: first, mechanism for feeding, printing, numbering, severing, and delivering a ticket;

second, mechanism for inserting in the printing-cylinder any one of a series of movable type-bars each bearing the name of a station, a symbol peculiar thereto, and, if desired, the price of the ticket to such station or destination; third, a series of manually-operated devices, such as keys, each bearing the name of a station on the road and each controlling the insertion of one of the movable type-bars into the printing-cylinder and the auditing mechanism and each arranged to release the power devices; fourth, auditing mechanism by means of which the number of a ticket, the destination printed thereon, and the amount paid therefor, or the total of all the money paid for the tickets preceding and including the ticket may be made upon the tally-sheet within the casing of the machine; fifth, devices for furnishing power or movement to the movable portions of the mechanisms just referred to.

First, referring to the mechanism for printing, numbering, feeding, severing, and delivering the tickets, the strip A of paper, upon which the tickets are to be printed, is drawn from a reel (not shown) mounted below the machine at any convenient point. As the machine is usually placed upon a stand or table, the reel may be supported in a bracket underneath the table and the strip A may be drawn therefrom through an aperture in the base of the casing. The strip passes between two feeding-rolls a', the former of which is equipped with a movable printing or indenting attachment for dating the ticket and the latter of which is shod with rubber or any other suitable frictional material to coact with the roll a in gripping the strip A and feeding it upward. (See Fig. 11.)

The roll a is radially extended at a², so that the strip A is gripped and fed during a portion only of each rotation thereof. I have stated that in the roll a is mounted an attachment for printing the date upon the back of the ticket; but it will be understood, of course, that in place of the date or in addition thereto I may print or indent upon the back of the ticket any information desirable or necessary, such as the number of the train for which the ticket is sold or the hour of its sale. To permit the manipulation of the dating devices, the casing is provided with a swinging door A', through which access may be had to the roll a. The dating attachment 55 consists of a series of type-bearing rings a³, all movable independently of the others and all mounted eccentrically within the periphery of the roll a upon an eccentric a⁴, keyed to the shaft a⁵. Spring-latches a⁶ frictionally engage notches in the inner walls of the said type-bearing rings for the purpose of holding them in proper position to indent upon the rear face of the ticket the date, the hour, or the other suitable matter. I have contemplated mounting a small inking-roller in prox-

imity to the radially-extended portion a² of the roll a', so as to ink the rings. The shafts for the two coacting feeding-rolls a a' may be mounted in bearings on the casing, or a separate standard may be used for them, as shown in Fig. 1.

Arranged above the feeding-rolls are the printing-rolls, consisting of the printing-cylinder a⁷ and the impression-cylinder a⁸, the latter being shod with rubber or other suitable friction-producing material and the former being provided with the radially-extended portion a⁹, upon which is formed or secured the type for printing the ordinary reading matter on the ticket, such as the name of the railroad, the conditions of the use of the ticket, &c., as indicated in Fig. 40. The shafts for the two cylinders are journaled in the brackets before referred to and are geared together to rotate in unison by means of straight spur-gears a¹⁰ a¹¹. The feeding-roll a is provided with a gear-wheel a¹², and between the wheels a¹¹ a¹² is placed a pinion a¹³, by means of which power is transmitted to the feeding-roll a.

Mounted above the printing-cylinders is the device for severing the ticket after it is printed, consisting of a stationary blade a¹⁴ and a movable blade a¹⁵, mounted upon the end of a rock-shaft a¹⁶. A guide having a converging throat is placed between the severing mechanism and the printing-rolls, so as to guide the end of the strip accurately to the cutting-blades, as is indicated at a¹⁷. The shaft a¹⁰ is provided with an arm a²⁰, engaged and oscillated by a cam d²⁸ on a shaft d¹⁷, to be afterward described, the parts being so timed that the movable blade is not actuated until the ticket has been printed and carried upward to a predetermined point.

The printing-cylinder is provided with numbering devices, as shown in Figs. 13, 14, and 15, the said devices consisting of a series of numeral-bearing disks a²¹, each bearing numerals from "0" to "9," inclusive, and each rotating the next succeeding one one step for each entire rotation. The first disk is provided with a ratchet-wheel a²², to which is given a step-by-step movement by a pawl a²³, mounted upon the end of a spring-held lever a²⁴, journaled on the shaft of the cylinder a⁷, as shown in Figs. 14 and 15, this pawl-bearing lever being actuated automatically by the insertion of a movable type-bar into the printing-cylinder. The printing-cylinder is also provided with a longitudinal slot a²⁵, as shown in Figs. 7, 11, and 13, to receive the said type-bars, and the said lever is provided with a cam projection normally extending into the slot or aperture, so that when the type-bar is inserted, as shown in Fig. 15, the lever is swung upon its axis and the "units-disk" is moved forward one step.

The mechanism for inking the type upon the printing-cylinder may consist of an ink-

ing-ribbon c , wound upon the spool c' and taken up by a roll c'' , which may be actuated in any desired way by mechanism (not shown) driven by any convenient part of the machine. The ribbon passes over an idler c^3 in proximity to the printing-cylinder and around other suitable idlers or guides to hold it out of contact with the feeding-roll a' . A tension device suspended in a loop in the ribbon is indicated at c^4 . If found desirable, I have contemplated dispensing with the inking-ribbon and shoe the idler c^3 , with a covering of felt charged with ink, or, again, if circumstances warrant it, I have contemplated using both the ribbon and the ink-charged idler, as they may be desirable in printing certain kinds of stock employed for the ticket-strip. Now it will be seen that if means were not provided for partially withdrawing the strip after a ticket has been severed there would be a large amount of waste material on the end of each ticket, and hence I provide a tension device which withdraws the strip a sufficient distance to permit the extremity thereof to be engaged by the edge of the raised portion a^2 of the feeding-roll a , when the next ticket is to be printed. A weight b , having an aperture through which the strip A may pass, is provided with inwardly-projecting flaps or lips b' of resilient material, which yieldingly and frictionally engage the ticket between them. The weight normally rests upon stops b^2 , projecting out from brackets b^3 , supported upon the base of the casing and is limited in its upward movement by stops b^4 , projecting from the ends of the said brackets. (See Fig. 38.) When the feeding-cylinders engage the strip and carry it upward, the weight is carried upward with the strip until it strikes against the stops b^4 , after which the strip will be drawn between the resilient clamps or lips b' the required distance; but as soon as the end of the strip is released from the grip of the feeding-rolls, the weight will immediately drop, and consequently draw downward with it the strip a distance equal to the distance traversed by the weight in its upward movement, thus bringing the end of the strip down to a point sufficient to prevent a blank space upon the end of the next ticket. In addition to the weight acting as a tension and retracting device for the strip of paper it also performs the very important function of maintaining the strip of paper in alinement, since it returns always to its original position upon the stops b^2 after having been adjusted properly with relation to the paper by the engagement of its ends with the stops b^4 . The lower stops are provided with inwardly-projecting fingers b^5 , which aid in guiding the strip properly to the feeding-rolls.

Next, referring to the carrier for the movable type-bars and the mechanism for selecting any one of the said bars and inserting it in the printing-cylinder, attention is directed to

Figs. 1, 2, 3, 5, 6, 7, 17, 18, 19, 35, 36, and 37. The reservoir or carrier for the type-bars is indicated as a whole by d , and it consists of two traveling belts, tapes, or ribbons d' , of thin steel, passing around wheels d^2 d^2 upon the shaft d^3 and loose wheels d^4 d^4 on the shaft d^5 . Each belt is perforated at regular intervals to receive the heads of spring-pins d^6 , as shown in Figs. 35, 36, and 37, each pin being passed through a block d^7 and secured in place by folding the edges or lips d^8 on the blocks inward to clasp the belt. Projecting inwardly from each block is a lug d^9 to enter between two of the teeth of the said wheels, each wheel being grooved to receive a belt and the blocks thereon, as shown more particularly in Figs. 4 and 7. The two belts are so placed that the pins are arranged in pairs, those of each pair being diametrically opposite each other, so as to receive a type-bar d thereon, as shown in the said last-mentioned figures. The ends of the pins d^6 are slotted, so that they enter apertures in the type-bars and engage the walls thereof with a spring-pressure, whereby they hold the said bars firmly in place unless the latter are engaged and moved positively therefrom. There is secured upon each pair of pins one of the said type-bars, of which there may be as many as there are stations on the road. Upon each type-bar is placed a type indicating its particular station by name, the especial symbol employed to designate such a station or the number thereof, and any other words or symbols that may be necessary, as shown in the lower line of the ticket, Fig. 41, said type being placed on the inner edge of the type-bar, so that the outer edge is blank, as illustrated.

By mechanism which I shall now describe the carrier is moved to present a type-bar at a point opposite the aperture in the printing-cylinder, and the said bar is grasped at its ends and carried into the said printing-cylinder, which is provided with pins a^{25} in alinement with the pins d^6 in the blocks carrying said bar. The transferring mechanism consists of two slides d^{10} d^{10} , each notched to receive a type-bar and each sliding upon guide-bars d^{11} , supported by stationary brackets d^{12} , and each connected to an arm d^{13} , secured upon a rock-shaft d^{14} , mounted in bearings upon the base of the casing, one of the said arms being provided with a roll extending into a cam-groove d^{15} in a cam-disk d^{16} on the said shaft d^{17} , as shown in Fig. 4. Power is imparted to said shaft d^{17} by a bevel-wheel d^{18} thereon, in mesh with a bevel-wheel afterward referred to on one of the power-transmitting shafts, to be fully described. This shaft d^{17} is the one carrying the cam-disk d^{28} , which oscillates the arm a^{20} , by means of which the movable blade of the severing mechanism is actuated, and it is from this shaft that power is transferred to the printing-cylinder through the medium of inter-

meshing gears d^{20} d^{21} d^{22} d^{23} , the last-mentioned gear being mounted upon the shaft of the printing-cylinder a^7 . These gears are illustrated in detail in Fig. 33, as well as in Fig. 4. The gears d^{21} and d^{23} are provided with blanks d^{24} and d^{25} , respectively, to provide for the printing-cylinder being held stationary momentarily for the insertion of the type-bar thereinto and its withdrawal therefrom, the normal position of the said gears when the machine is at rest being shown in Fig. 3.

It being essential that the type-bar which is to be inserted in the cylinder should be in exact alinement with the aperture in the cylinder, so that it will slide properly upon pins a^{25} , I provide mechanism for properly positioning or centering the wheels d^2 d^3 , both of which are fast upon their shaft d^3 . Secured within the outer rim of one of the wheels d^2 is a ring d^{26} , having inwardly and radially projecting teeth, forming notches to receive a finger d^{27} , projecting axially inward from the slide d^{10} . The teeth are tapering, so that the notches converge, and hence when the slides start upon their movement to transfer the type-bar from the carrier into the printing-cylinder the pin d^{27} enters a notch, and if the wheel is not in the exact required position the pin will shift it slightly to bring the pins d^7 into alinement with the pins a^{25} before the said type-bar d has a chance to encounter the latter.

The transferring-slides d^{10} d^{11} are so arranged that they have inwardly-projecting fingers or parts between which the type-bars are moved, as shown particularly in Fig. 7.

I shall now proceed to describe the mechanism for actuating the reservoir or carrier to present the proper type-bar to the transferring mechanism by means of which it is placed in the printing-cylinder. Upon the shaft d^3 are placed two sprocket-wheels e e' , the former of which is loose upon the shaft d^3 and the latter of which is rigidly secured thereto. An endless belt or ribbon e^2 , having perforations to receive the teeth on the said wheel e , passes from the said wheel around an idler e^3 near the right-hand end of the machine, a large positively-driven sprocket-wheel e^4 and another idler-wheel e^5 , back to the wheel e . Another endless belt e^3 passes around the wheel e' and around an idler e^6 by the side of the wheel or idler e^3 . The two idlers e^3 e^6 are both mounted upon a stud-shaft projecting out from a bracket e^8 , mounted upon the partition e^9 , the idler e^6 being likewise journaled on a stud projecting out from a bracket e^8 . A longitudinally-grooved shaft f , secured at its ends in the casing and in a frame-bar f' , is arranged parallel to the lower stretch of the two endless belts, and keyed to slide upon the said bar is a carriage f^2 , having a projection f^3 , apertured to permit the belt e^2 to pass loosely there-

through and rigidly secured to the belt e^8 , which, as before stated, passes about the sprocket-wheel e' , fast upon the shaft a^3 of the type-bar reservoir or carrier. The said carriage is movable from end to end of the bar f , being moved back and forth by the belt e^2 to convey movement to the belt e^8 and the type-bar reservoir or carrier. By mechanism which I shall subsequently explain the belt e^2 is driven first in one direction for a predetermined distance and then in the opposite direction through the same distance, and for the purpose of presenting the proper type-bar to the printing-cylinder I provide devices for temporarily connecting the carriage to the belt e^2 to cause it to travel therewith far enough to bring the said type-bar into alinement with the aperture in the said cylinder. The mechanism for connecting the carriage with the said belt e^2 is illustrated more particularly in Figs. 16, 17, and 18, to which reference may now be had. Pivoted in a lug f^4 , projecting downward from the carriage f^2 , is a rock-shaft f^5 , having on one end an arm f^6 and on the other end an arm f^7 . The arm f^6 is provided with an upwardly-projecting gripper f^8 , projecting through an aperture in the projection f^3 of the carriage and adapted to coact with a suitable gripping-jaw f^9 , arranged oppositely thereto and secured in an aperture in the said projection f^3 . These two jaws f^8 f^9 may be constructed of rubber or other suitable material and are small enough in cross-diameter to project into the apertures in the belt f^2 , as shown in Fig. 16, to temporarily connect the carriage and belt together. A spring f^{10} is secured to the said lug f^4 and tends to normally force the movable jaw or clamp f^8 against the jaw or clamp f^9 . The said clamp f^8 , however, is normally held out of engagement with its coacting jaw by a cam f^{11} , secured upon the end of the arm f^7 , said cam engaging a finger g , projecting outward from a slide-bar g' , movable in guides g^2 g^3 on the side of the frame f' , before referred to. When the said carriage is at the left-hand end of the guide-bar f and the machine is at rest, the cam f^{11} on the arm f^7 is in engagement with the said finger g , and the arm f^6 is held downward, whereby the belt f^2 is free to travel relatively to the carriage. To disengage the finger g from the said cam and permit the carriage to travel with the belt f^2 to any predetermined point, I employ the following mechanism: Fulcrumed on a cross-bar h (shown best in Fig. 4) are manually-operated levers h' , projecting out through the casing and each one provided with a key h^2 , bearing the name of a station on the road. The keys are banked, as in a cash-register or type-writer, and the names of the stations may be arranged in alphabetical order or according to their numbers, as may be desired. The levers h' are normally held upward

against a cross-bar h^3 by springs h^3 , bearing upon a cross-bar h^4 , which is provided with a cushioning-strip h^5 , as shown in said last-mentioned figure. Each key is likewise provided with a downwardly-projecting portion h^6 upon its end, as at h^7 , passing between two pins h^8 , extending between cross-bars h^9 h^{10} immediately in front of the guide rod or bar f . When the said keys are placed side by side, they occupy a space equal in length to the distance traveled by the carriage f^2 , and when one of the keys is depressed its end h^7 projects into the path of a lug f^{11} on the carriage and into the path of the said cam f^{11} to 10 depress the same and separate the clamping-jaws f^8 f^9 . There is one key for each type-bar in the reservoir or carrier, and each one 15 stops the carrier at the proper point to have its corresponding bar delivered to the printing-cylinder. Arranged below the said horizontal cross-bar h^4 is a slotted rotary tube i , mounted in bearings in suitable frame-bars in the casing. Each key-lever h^1 is provided with a depending projection or foot h^{13} , 20 adapted to engage the edge of the slot in the said tube and partially rotate the same, whereby each lever when depressed will cause a partial rotation of the said tube. The latter is provided with a cam i' , as 25 shown in Figs. 4, 17, and 18, to engage the upwardly-extended end of the slide g' and thrust the said slide forward for the purpose of releasing the cam f^{11} and lever f^7 and permitting the clamping-jaws to connect the 30 carriage to the belt f^2 . A spring g^4 normally holds the slide in position to cause the engagement of the finger g with the said cam. A slide g^5 is placed below that at g' and is provided with an upturned end g^6 to engage 35 the edge of the cam i' after it has been partially rotated and hold the tube against backward movement. A spring g^7 normally holds the slide g^5 in position to engage the cam i' ; but it is moved forward temporarily to release the tube i by a bell-crank lever g^8 , fulcrumed upon a bracket g^9 , extending out 40 from the frame-bar f' and connected to the slide, and a pivoted dog g^{10} , fulcrumed on one of the type-bar-transferring arms d^{13} , before referred to. A spring g^{11} holds the dog 45 against a pin g^{13} , so that the bell-crank lever is operated positively when the type-bar is transferred from the printing-cylinder to the reservoir or carrier and the dog slides freely 50 under the bell-crank lever when a type-bar is being transferred from the carrier to the printing-cylinder.

Now then from the description thus far given it will be seen that if the belt e^2 be driven positively and one of the keys h^2 be depressed the end h^7 of the key-lever will be thrown into the path of the lug or stop on the carriage and into the path of the cam f^{11} . The depression of the lever will cause the foot 55 h^{13} to engage the cam-tube and partially ro-

tate the same, whereupon the cam i' will engage the slide g' and thrust the finger g away from the cam f^{11} . Then the clamping-jaws close upon the tape or belt f^2 , and the carriage is drawn along with the said tape or belt 70 until the cam f^{11} and the lug f^{12} engage the end h^7 of the lever, whereupon the carriage immediately stops and is released from the belt or tape f^2 . The movement of the carriage causes a corresponding movement of 75 the type-bar carrier or reservoir, and the type-bar is now ready to be carried by the transferring device into the printing-cylinder. As soon as the printing-cylinder has rotated the transferring device carries the 80 type-bar back to the reservoir, and in so doing the dog g^{10} engages the bell-crank lever g^8 and the slotted tube i is allowed to return to its normal position and releases the foot of the key-lever h^1 . Thus the slotted tube not 85 only guides the trip mechanism for releasing the clamping device on the carriage, but it also holds the key-lever depressed and prevents the depression of another lever until the type-bar is returned from the printing- 90 cylinder to the reservoir or carrier. The springs h^3 on the key-levers are sufficient to raise the said levers and return the slotted tube to its original position. Thus it will be seen that each key controls the insertion of 95 its particular type-bar into the printing mechanism and also controls the operation of the clamping device for temporarily connecting the carriage with the traveling belt or tape. 100

Referring now to the auditing mechanism, the second sheet B is drawn from the roll j , mounted in the standards j' , projecting upward from the base of the casing, and passes over a shaft k , extending longitudinally of 105 the machine (to which reference will be subsequently had) and between rollers l l' , the latter of which is shod with rubber. From thence the sheet passes over a stationary shelf or ledge m and beneath a movable blade 110 m' , held upward from the ledge by a spring m^2 and adapted to be thrown down against it by a handle m^4 on the shaft m^5 of the said movable blade. By depressing the handle m^4 downward to press the edge of the movable plate or blade m' against the shelf m the projecting edge B' of the strip may be torn off from the body thereof. Mounted upon the said shelf k is a dog k' , engaging the periphery of a cam k^2 on a longitudinally-arranged 115 shaft n . The hub of the dog is provided with an arm k^{21} , connected by a link k^3 with an arm k^4 , loose on the shaft of the roll l and carrying a pawl k^5 to engage a ratchet on the said roll and impart a step-by-step movement 120 thereto. Likewise mounted upon the said shaft k is another arm or dog k^6 , precisely similar to that at k' , but having secured thereto an arm k^7 , extending to the front. The dog k^8 is rigidly secured to the shaft k , while the 125 130

dog k' is loose relatively thereto. The dog k^6 likewise rests upon a cam k^8 , having its depression slightly in the rear of that in the cam k^2 , so that the dog k^6 is actuated a few seconds after the dog k' has been moved. Another arm projects out from the shaft k at its right-hand end, (this not being shown,) and between the two arms is extended the movable platen k^9 , a spring k^{10} , tending to raise the platen, being connected to the arm k' in a stationary portion of the machine. This platen k^9 may be formed of any suitable material, and, as shown, it is provided with a trough or groove k^{11} , which may be filled with coloring-matter. Secured to the carriage and projecting downwardly and forwardly therefrom is an arm o , having upon the end thereof the stylus or pointer o' directly above the groove k^{11} in the platen k^9 . The arm o slides below a shaft p , extending longitudinally of the machine, whereby it is braced against upward pressure when the platen is thrust upwardly. The auditing-sheet being ruled to have as many spaces as there are stations and keys and each space being equal to the distance between the ends h' of the keys, it will be seen that when the ratchet is stopped in its movement by any one of the said keys and the platen is raised it will strike the auditing-strip B against the stylus o' , which will perforate the strip in the space devoted to a particular station. The auditing-strip is shown in detail in Fig. 39. In addition to the paper being perforated the coloring-matter enters the aperture therein and discolors it or stains it in such way that the attention of the auditor of the road is directed to the perforation, and there is no chance to erase it without betraying such fact. On one edge of the auditing-strip is printed the number of the ticket sold, and on the other edge is printed the amount of the sales, including the price of that ticket, so that the price of each ticket can be ascertained by subtracting the total of the sales of the preceding ticket from the total of sales opposite thereto.

The numbering devices are illustrated in Figs. 20 to 24, inclusive. Projecting upwardly from the shaft k is an arm q , connected to an arm q' on the shaft p , before referred to. The said arm q' carries a pawl q^2 , which is adapted to engage and impart a step-by-step movement to a ratchet-wheel q^3 , connected to a numeral-disk q^4 , said disk being that of the units. The said disk is provided with a series of projections bearing the numerals "0" to "9," inclusive, and the lowermost numeral is substantially in the same horizontal plane as the end of the stylus o' , so that when the platen is moved upwardly it strikes the paper not only against the stylus, but also against the numeral on the disk q^4 . Placed by the side of the numeral-disk are other disks q^5 , q^6 , q^7 , and q^8 , bearing numerals designating tens, hundreds, thousands, and tens

of thousands. Each succeeding disk is actuated one step at each complete rotation of the preceding disk by means of a spring-pawl q^9 , rotating with the preceding disk and engaging teeth q^{10} on the adjacent disk. Each pawl is thrust outward once in its revolution by a cam q^{11} , keyed upon the shaft p , being provided with a projecting side portion to engage the cam. The disks are centered by spring-dogs q^{12} , formed on the hub of the cams q^{11} . (See Fig. 20.) It will be seen that each time the platen is actuated and returns to normal position the units-disk will be rotated one step to indicate the number of the next ticket to be printed.

In Figs. 1, 6, 7, and 25 to 32, inclusive, is shown more particularly the mechanism for printing upon the auditing-sheet the total of sales opposite and including each ticket.

The shaft n , which was hereinbefore referred to as carrying the cams k^2 and k^8 , is provided on its end with a beveled wheel n' , (see Fig. 6,) meshing with and driving a beveled wheel n^2 on a shaft n^3 , arranged transversely of the machine and mounted in brackets n^4 , as shown in said last-mentioned figure. Upon the shaft n^3 are placed three cams n^5 , n^6 , and n^7 , each rocking a hub n^8 , n^9 , and n^{10} , respectively, on a shaft placed below the shaft n^3 , by engaging an arm projecting upwardly from the hub. Mounted loosely on the shaft p at the end opposite to that carrying the numbering-disk are placed disks r , r' , r^2 , r^3 , r^4 , and r^5 , indicating cents, dimes, dollars, tens of dollars, hundreds of dollars, and thousands of dollars, each disk bearing the numerals "0" to "9," inclusive. The disks r^3 , r^4 , and r^5 are advanced step by step, each taking its motion from the preceding disk, and the disk r^3 being driven from the disk r^2 ; but the disks r , r' , and r^2 are each provided with a pinion r^6 , r^7 , and r^8 , connected with and driven by gear-wheels, the said gear-wheels being indicated by r^9 , r^{10} , and r^{11} , respectively. Each disk is centered by a dog r^{12} , engaging with notches in a disk r^{13} , carried by each of the numeral-bearing disks r , r' , and r^2 , and each disk is provided with a ratchet-wheel r^{14} , with which a dog r^{15} , carried by the preceding disk, may engage. Of course the disk r is not provided with a ratchet-wheel, as it is driven directly by its gear r^9 ; but it is provided with a pawl r^{16} , which engages the ratchet-wheel on the next succeeding disk r' . The said dog or pawl r^{15} is drawn into engagement with the ratchet-wheel r^{14} once during each rotation of the disk which carries it by an arm r^{17} , which is held upward by a spring r^{18} , strong enough to overcome the spring r^{19} , by which the said dog or pawl is held radially outward from the disk. The arm r^{17} is made to yield, so that if the parts be in the position shown in Fig. 30 and the disk r' is rotated positively by the gear r^{10} the arm r^{17} will yield to permit the

projecting edge r^{20} of the pawl to pass it. This arrangement of faces or ratchets is moved for the purpose of imparting one step to the rotation of the disk r' in addition to its movements caused by the gear r^{10} by the disk r completing one entire revolution, as well as to cause a similar movement of the disk r^2 when the disk r' has made a complete rotation. The gears r^9 , r^{10} , and r^{11} and their respective shafts s , s' , s^2 receive motion from the following devices:

Rigidly secured upon each shaft s , s' , or s^2 is a ratchet-wheel t , with which a spring-held pawl t' on an arm t^2 , loosely mounted on said shaft, may engage. The hub of each arm t^2 has partially coiled thereon a cord or wire t^3 , connected to an arm n^{11} , projecting out from each of the three hubs n^8 , n^9 , and n^{10} , before referred to, the said hubs being rocked sufficiently to cause the pawls t' to carry their respective ratchet-wheels at least a distance equal to the length of the teeth thereon, so that, if there were nothing to prevent, each time one of the hubs was rocked each of the ratchet-wheels t would be advanced nine steps or nine teeth by the pawls t' . Loosely mounted on the shaft s are the hubs t^4 of curved guards or hoods t^5 , partially encircling each of the ratchet-wheels t , and the said hubs t^4 are provided with segmental gear-teeth t^6 , with which rack-teeth t^7 on three slides t^8 , t^9 , and t^{10} engage. (See Figs. 7 and 25.) There are nine rack-teeth t^7 on each slide, and each slide is connected to a spring u , which tends to draw it forward a distance sufficient to cause the rack-teeth t^7 to rotate the gear far enough over the ratchet-wheel t to cover nine teeth thereon, so that if the pawl t' were moved forward it would have no effect upon its ratchet-wheel, since it would be held out of engagement with the teeth thereon. The said slides, however, are normally held against forward movement by a dog u' , mounted upon a bracket u^2 , secured upon a part of the casing, as shown in Fig. 25, which dog engages a shoulder t^{11} on each slide.

On the rear of the shoulder t^{11} on each slide there are nine ratchet-teeth t^{12} , with which the said spring-pawl u' may engage, and the pawl is raised to allow the springs u to draw the slides forward by a link u^4 , connected to the outer end of the pawl and to the end of a tilting lever u^5 . (Shown best in Fig. 29.) A spring-held dog u^6 , mounted upon one of the arms d^{13} of the type-bar-transferring device, engages the lever u^5 when the said transfer mechanism is actuated to carry a type-bar from the reservoir to the printing-cylinder or to raise the free end of the pawl and release the slides, the said dog being spring-held in such way that it may slide freely under the end of the lever u^5 without moving it when the type-bar is carried back to the reservoir. The said lever u^5 is mounted upon a

bracket u^7 , projecting out from the part of the framework in the casing.

Each of the type-bars before referred to is peculiarly formed on its forward end, as best shown in Fig. 38^a—that is to say, the end of each type-bar is divided into three parts 20, 30, and 40, which when the said type-bar is first placed in the printing-cylinder or in alinement with the slides t^8 , t^9 , t^{10} , respectively, each portion acts as a stop for each particular slide to limit the movement thereof, and thereby regulate or determine the distance the guard t^5 is moved over the ratchet wheel t .

By referring to Fig. 38^a it will be seen that I have shown the end of the type-bar as being divided crosswise into as many spaces as there are teeth on the slide, each space indicating a numeral, the spaces in line with the portion 20 of the edge indicating dollars, that in line with the portion 30 indicating dimes, and that in line with the portion 40 indicating cents. Now suppose that the ticket printed by the said type-bar shown in the said figure cost "\$3.58." It will be seen that when the type-bar is in alinement with the three slides t^8 , t^9 , t^{10} and the pawl u' is lifted the said slides will be drawn forward by their springs u until they rest against the said portions 20, 30, and 40. The slide t^8 will move forward a very short distance, so that its rack-teeth t^7 will engage the pinion t^6 of the gear and revolve the said gear sufficiently to cover one tooth of its ratchet-wheel. The slide t^8 will move forward four spaces, and its guard will cover four teeth of its pawl. The slide t^{10} will cause its respective guard to cover six teeth of its ratchet-wheel. Now when the hubs n^8 , n^9 , n^{10} are rocked by their respective cams and the pawls t' are oscillated through an entire movement the cents ratchet-wheel will be moved eight teeth, the dimes ratchet-wheel will be moved five teeth, and the dollar ratchet-wheel will be moved three teeth. Thus the movement of the three ratchet-wheels is imparted to their respective gear-wheels 9, 10, and 11. The ratchet-wheels are operated one after the other and not in unison. Immediately after the pawls t' have been oscillated the slides are withdrawn by a bell-crank lever v , actuated by a pin on a disk v' on the shaft n^3 , the upper end of the bell-crank lever v engaging the downwardly-bent ends t^{20} of the slides. As soon as the bell-crank lever draws the slides back to their normal position the pawl u' drops behind the shoulder t^{11} and prevents their being brought forward again by the springs until the dog is tripped by the pawl u^6 on the transfer mechanism. In order to prevent the slides from moving forward when the type-bar is carried around in the printing-cylinder, the end of the pawl u' engages the ratchet-teeth t^{12} on the slides. Thus it will be seen that as each type-bar is

formed on its end to correspond to the price of the ticket to the destination on the said bar the hoods or guards will cover their respective ratchet-wheels, so that the pawls 5 will move the ratchet-wheels a number of teeth to cause the numeral-disks to print the total of sales on the auditing-strip, including the price of the ticket last sold.

The disks r to r^6 , inclusive, are mounted, 10 as aforesaid, on the shaft p , and they are equal in circumference to the numbering-disks, so that when the platen k^9 is actuated the record-sheet or the auditing-sheet will bear a record of the destination on the ticket, 15 the number of the same, and the total of sales, including the said ticket. All of the tickets for one particular station are indicated on a certain line on the auditing-sheet, so that the number of tickets sold to that station may be easily ascertained by running the eye along the line.

Inking-ribbons u^{20} u^{21} are drawn between the numbering-disks and the adding-disks and the record-sheet. (See Figs. 4 and 5.)

25 They are drawn from reels u^{22} u^{23} by rolls u^{24} u^{25} , the latter being provided with ratchets engaged and turned by pawls u^{26} , connected with the levers k^4 , which carry the pawls k^5 for turning the record-sheet-feeding roll. 30 The said levers k^4 are actuated by the arms k' , as hereinbefore described.

Power is applied to various mechanisms, forming a part of the machine, as follows: 35 w is a shaft mounted in suitable bearings and projecting through the end of the casing to receive a crank w' (see Fig. 7) and upon which the said shaft is mounted, the gear-wheel w^2 intermeshing with and driving a gear-wheel w^3 , one-half the size thereof, keyed 40 upon a shaft w^4 . Pinned upon the said shaft is a winding-drum w^5 , around which is coiled a rope or wire w^6 , having on the end thereof a weight, (indicated conventionally in Fig. 5.) Pivoted upon the outer face of the 45 winding-drum are pawls w^8 and w^9 , respectively, engaging ratchet-wheels w^{10} w^{11} . The ratchet-wheel w^{11} is rigidly secured upon the hub of a gear-wheel w^{12} , having only one-half of its circumference toothed and operative. The ratchet-wheel w^{10} is mounted 50 upon the hub of a quadrant-shaped beveled gear-wheel w^{13} , whose teeth are arranged diametrically opposite the teeth on the gear-wheel w^{12} . When the crank w' is drawn forward to impart half a rotation to the shaft w and the wheel w^2 , the wheel w^3 and the drum are caused to make one complete rotation. The pawls w^8 w^9 slide freely over the ratchet-wheels w^{10} w^{11} , the wheels w^{12} w^{13} remaining 55 stationary. When the trip or detent, to be afterward described, is actuated by the depression of one of the keys and the winding-drum is free to rotate, the weight w^7 will impart a complete rotation to the said winding-drum and the wheels w^{12} and w^{13} through the 60

medium of the pawls w^8 w^9 and their respective ratchet-wheels w^{10} and w^{11} . The hub of the wheel w^{13} is rigidly secured upon a sleeve w^{14} , mounted loosely upon the shaft w^4 , and upon the said sleeve is secured another segmental bevel-wheel w^{15} , a quadrant in form and having its teeth arranged as a continuation of those of the teeth of the bevel-wheel w^{13} . Upon the hub of the wheel w^{15} is a gear-wheel w^{16} , intermeshing with a driving-pinion w^{17} , rigidly secured upon a shaft w^{18} and formed upon the hub of a gear-wheel w^{19} . Mounted loosely upon the shaft w^{18} is a gear-wheel w^{20} , having secured thereto or formed thereon a bevel-wheel w^{21} , engaged with a driving-wheel w^{22} on a vertically-arranged shaft w^{23} , having on its upper end a governor or speed-regulator consisting of a series of fan-blades w^{24} . The shaft w^{25} is arranged in parallelism with the shaft w^{18} , and it is provided with a pinion w^{26} , intermeshing with and driven by a large wheel w^{19} , and with a large wheel w^{27} , engaging with and driving a pinion w^{28} , as before referred to. Thus with this multiplying-gearing the shaft w^{23} is rotated at a very high rate of speed, and the governor device secures the even and regular movement of the various parts of the machine. The yoke w^{28} , in which the shaft w^{23} is mounted, has fulcrumed to it a detent x , 95 adapted to engage a cam-stop x' on the shaft w^{23} . The detent-lever x is connected by links x^2 x^3 x^4 x^5 x^6 and bell-crank levers x^7 x^8 x^9 x^{10} with a lug or cam i^4 , projecting downwardly from the slotted tube i , hereinbefore 100 described. The link x^6 is threaded at its ends to receive an adjustable stop-nut x^{11} , with which the cam i^4 may engage to shift the levers and links and withdraw the detent x from the cam x' on the shaft w^{23} , these 105 parts being shown in Fig. 34. As soon as one of the key-levers is depressed and the slotted tube i is rocked in the manner hereinbefore set forth the cam i^4 shifts the links x^6 and the detent is withdrawn from the cam 110 catch or stop on the shaft w^{23} , and the weight w^7 is then free to rotate the drum and the various parts connected therewith. As soon as the key-lever rises and the shaft w , having the clamp, returns to its normal position, the 115 projection x^{12} on the said shaft engages an arm x^{13} , extended out from the bell-crank lever x^9 , and shifts the said lever and the parts connected therewith to throw the trip or detent x into engagement with the cam x' on the shaft w^{23} . In place of the cam x' I may 120 employ a ratchet-wheel, if desired. Thus it will be seen that although the weight is wound up the machine is not free to start until the key-lever is depressed and the detent is drawn out of engagement with the cam x' . The gear-wheel w^{12} , before referred to, intermeshes with and imparts a movement during 125 the middle half of its rotation to a gear-wheel y , mounted upon the end of the shaft n , be- 130

fore referred to, and through the said shaft and the bevel-wheels $n' n^2$, before referred to, (see Fig. 6,) motion is transferred to the shaft n^3 to impart power to the adding mechanism for printing the amount of sales on the auditing-strip. The shaft n is also provided with cams k^2 and k^8 , before referred to, through which mechanism is actuated to feed the record-sheet and operate the platen, 5 and the said shaft also carries the bevel-wheel y' , (see dotted lines in Fig. 4,) which intermeshes with and drives the bevel-wheel d^8 on the shaft d^{17} , which furnishes movement to the type-bar-transmitting mechanism and 10 the printing mechanism for the tickets. The segmental bevel-wheels w^{13} and w^{15} engage and drive in opposite directions alternately a bevel-wheel y^3 , mounted on the shaft y^4 , (see Figs. 8 and 10,) the said shaft y^4 carrying a 15 gear-wheel y^5 .

The operation of the machine is as follows: Suppose a traveler wished to obtain a ticket at the station "Boston" to the station "Winchester" and the fare or price of the 20 said ticket is one dollar and sixteen cents. The station agent grasps the crank w' and draws it toward him to impart a complete rotation to the drum w^6 and wind up the weight. The detent x , before referred to, is 25 at this time engaged with the cam-stop x' on the governor-shaft w^{23} , so that although the drum is wound up the various mechanisms are held against rotation. The station agent depresses the key bearing upon it the 30 name "Winchester." As the key moves downward its foot h^3 engages the edge of the slot on the tube i and partially rotates the tube, and simultaneously therewith its end h^7 projects into the path of the cam f^{11} and the 35 stop f^{12} on the carriage f^2 , carrying the stylus o' . As the tube i is rocked it first moves the detent x to release the governor-shaft and permit it to rotate, and it also thrusts forward the slide g' to cause the finger g to release the cam f^{11} and arm f^7 and permit the 40 clamping-jaws $f^8 f^9$ to connect the carriage to the tape e^2 . As soon as the detent x releases the governor-shaft w^{23} the weight w^7 begins to rotate the drum and the parts connected therewith, the segmental bevel-gear w^{16} begins to rotate the bevel-wheel y^3 in the direction shown by the arrow in Fig. 8, and through the intervening gears the 45 sprocket-wheel e^4 is rotated in the direction of the arrow shown thereon in Fig. 3, and the belt e^2 , carrying with it the carriage, is drawn along. As soon as the cam f^{11} upon the arm f^7 and the stop f^{12} engage the end h^7 of the key which has been depressed, and which is 50 held from rising by the end of its foot being inserted in the slot in the tube i , the clamping members $f^8 f^9$ release the tape f^2 , and it continues its travel, while the carriage remains stationary. The carriage in its travel, by 55 reason of its rigid engagement with the tape

or belt e^2 , rotated the shaft e^3 , of the type-bar reservoir sufficiently to bring the type-bar for the Winchester station in alignment with the aperture or slot in the printing-cylinder a^7 , which during this time is stationary and 70 is waiting to receive it. At this time the shaft d^{17} , which receives its movement from the shaft n , is rotated far enough to cause its cam d^{16} to swing the levers d^{13} of the transferring mechanism on their pivot-shafts d^{14} , 75 and as the said arms d^{13} move forward and carry the type-bar into the printing-cylinder, at first properly centering the wheel d^2 , as hereinbefore described, and then transferring the type-bar into the printing-cylinder, in 80 which it is held by the ends of the spring-pins d^{25} separating and holding it by spring-pressure. As the said arms d^{13} swing over, the dog u^6 thereon engages the lever u^5 (see Figs. 25 to 29) to raise the pawl u' , this occurring 85 at the very last of the movement of the said bars d^{13} . The said slides $t^8 t^9 t^{10}$ immediately spring forward and their ends engage the end of the type-bar, the end of the said type-bar being formed to correspond to the 90 numerals 1 1 6, (being the price of the ticket.) The hoods or shields t^6 are actuated to cover the ratchet-wheels t or so much thereof that the pawl t' can only move the "dollar" 95 ratchet-wheel one step, the "dimes" ratchet-wheel one step, and the "cents" ratchet-wheel six steps, the pawls being actuated by the cords or wires t^8 , the arms n^{11} , the hubs $n^8 n^9 n^{10}$, the cams $n^5 n^6 n^7$, the bevel-wheel n^2 , and the bevel-wheel n' on the shaft n . 100 As soon as the slides $t^8 t^9 t^{10}$ spring forward the pawl u' drops into engagement with the teeth t^{12} and holds them against backward movement. Then through the gearing (previously described, and illustrated in Figs. 11 and 33) the feeding-rolls $a' a'$ and the printing and impression-cylinders $a^7 a^8$ are rotated once. It may be first stated that when the type-bar was inserted in the printing-cylinder arm d^{13} engaged the lever a^{24} and 110 caused the pawl a^{23} to rotate the numeral-disk a^{21} one step. The rotation of the printing and feeding devices carries the ticket above the movable blade a^{16} , which is actuated to sever the ticket. In the meantime 115 the slides $t^8 t^9 t^{10}$ are all drawn forward to their inoperative positions by the bell-crank lever v , and during the time that the printing and feeding devices are operating the platen is raised to stick the record-strip against the stylus o' and against the numbering-disks on the one end of the shaft p and the disks on the other end of the shaft p , which print on the auditing-sheet the total of sales, including the ticket now being printed. After the printing-cylinder makes one complete rotation the transferring mechanism is actuated to return a type-bar to the reservoir, and in so doing the dog g^{10} on the arm d^{13} engages the bell-crank lever g^8 (see Fig. 18) to release the 120

slotted tube i and permit the key-lever to rise, and as the said slotted tube i rocks to its normal position the end of the key h^7 is withdrawn from the cam f^{11} , and the belt or tape e^2 being now driven in the opposite direction the carriage is connected thereto to return it to its original position, and as it travels back it moves the type or reservoir back to the position it originally occupied, and as the crank w' reaches the end of its movement the cam x^{12} on the shaft w causes the detent x to again engage the cam-stop x' from the shaft w^{23} , and the machine comes to a state of rest.

In order to point any number of tickets to the same destination, I mount a lever z in a bracket z' , mounted in the frame of the machine, which may be moved into engagement with a cam z^2 . (Shown in dotted lines in Fig. 4.) This cam is on the end of a slotted tube i and operates to hold it against a reverse movement after it has been once rocked. When this lever z^0 , which projects through a slot in the casing of the machine, is in engagement with the cam z^2 , a ticket will be printed for the same station each time the crank is drawn forward by the station agent.

Instead of the weight-motor I may employ a mechanical or electrical motor or a manually-operated power device of any kind, so that the printing of the tickets when the lever z is in its operative position will be continuous.

The casing is provided with a door C in Fig. 4, which may be secured by a lock, the key to which is held only by the official whose duty it is to collect the auditing-strips. The door may be opened to permit access to the strips, whereby the ends thereof may be torn off.

I claim—

- 40 1. A machine of the character specified comprising printing mechanism including two coacting members adapted to receive between them the material to be printed, a series of type-bars, and manually-controlled mechanism for selecting any one of said type-bars and automatically transferring it into printing position in one member of said printing mechanism including a plurality of keys equal in number to said type-bars.
- 45 2. A machine of the character specified comprising printing mechanism including two coacting members adapted to receive between them the material to be printed, a series of type-bars adapted to be moved into printing position in one member of said printing mechanism, and mechanism including a series of manually-operable keys for selecting any one of said type-bars, and moving it into printing position.
- 50 3. A machine of the character specified comprising ticket-printing mechanism including two coacting members adapted to receive between them the material to be printed, a series of movable type-bars, mechanism adapted to insert any one of said type-

bars in one member of the printing mechanism, and devices, one for each type-bar, for controlling the insertion of a type-bar in the said printing mechanism.

4. A machine of the character specified comprising printing mechanism including two coacting members adapted to receive between them the material to be printed, a series of movable type-bars each adapted to be inserted in one member of said mechanism, a carrier for said type-bars, automatic mechanism for inserting a type-bar into the printing mechanism, and a series of keys, one for each type-bar, for selecting a type-bar to be inserted by said automatic mechanism.

5. A machine of the character specified comprising printing mechanism including two coacting members adapted to receive between them the material to be printed, a series of type-bars each adapted to be inserted in one member of the printing mechanism, a carrier for said type-bars, power devices for moving said carrier, automatic mechanism for inserting any one of said type-bars in the printing mechanism, and a series of keys, one for each type-bar, each controlling the said power devices, and the said type-bars.

6. A machine of the character specified, comprising printing mechanism, a carrier having a series of removable type-bars, transferring mechanism for carrying a type-bar from the carrier to the printing mechanism and back again, and manually-controllable means for moving said carrier to present any one of said type-bars to said transfer mechanism.

7. A machine of the character specified, comprising a printing-cylinder, a carrier or support for a type-bar, mechanism for moving said type-bar to the printing-cylinder, and subsequently back to the carrier, and mechanism for imparting a rotation to said printing-cylinder when the type-bar is therein.

8. A machine of the character specified, comprising printing mechanism, an endless carrier having a series of type-bars, each adapted to form a part of said printing mechanism, normally locked power devices for moving the carrier, and a series of keys each arranged to release the power devices, and arrest the carrier at a predetermined point.

9. A machine of the character specified, comprising printing mechanism, a series of type-bars for said printing mechanism, an endless carrier for said type-bars, power devices having a predetermined movement, means for connecting said carrier with said power devices, and a series of manually-controlled keys each arranged to disconnect the carrier from the power devices at a predetermined point.

10. A machine of the character specified, comprising printing mechanism, a carrier having a series of type-bars, means for transferring a type-bar to the printing mechanism

- and subsequently back again, power devices for shifting said carrier, and a series of manually-controlled keys each adapted to arrest the carrier at a predetermined point, and 5 mechanism for holding the key in its operative position until the type-bar has been transferred from the printing mechanism to the carrier.
11. A machine of the character specified, 10 comprising printing mechanism, a series of type-bars, manually-controlled mechanism for selecting any one of said type-bars and moving it into operative position as a part of said printing mechanism, and a carrier for 15 said type-bars having provisions for receiving said type-bars, and wheels or pulleys for supporting said carrier.
12. A machine of the character specified, 20 comprising a carrier having a series of printing devices, a power-wheel, parallel endless belts one driven by the wheel and the other connected to the carrier, and manually-controlled mechanism for temporarily connecting the two belts together.
- 25 13. A machine of the character specified, comprising a carrier having a series of printing devices, suitable power devices, two endless belts, one connected to the carrier and the other connected to the power devices, a 30 carriage having means for temporarily connecting the belts together, and a series of manually-controlled keys each arranged to operate the mechanism on the carriage to connect the belts together and then to arrest 35 the carriage at a predetermined point.
14. A machine of the character specified, comprising a carrier having a series of printing devices, suitable power devices, two disconnected endless belts one connected to the 40 carrier and the other connected to the power devices, a carriage connected to the carrier-belt, and having mechanism for connecting it to the power-devices belt, and a series of keys each adapted to temporarily operate the 45 mechanism on the carriage to connect the two belts together, and each arranged to project into the path of the carriage.
15. A machine of the character specified, 50 comprising a carrier having a series of printing devices, a belt, automatic devices for moving said belt in one direction, an arbitrary distance and then returning it to original position, and manually-controlled devices arranged to connect the carrier and the belt 55 temporarily until the carrier reaches a predetermined point, when the belt is moving forward, and then connecting it to said belt whereby it is returned to original position.
16. A machine of the character specified, 60 comprising a carrier having a series of printing devices, a positively-driven belt, a carriage connected to the carrier in proximity to said belt, grippers carried by the carriage for engaging the belt, means for normally holding 65 the gripper open, and a series of keys each 70 operating said means to cause it to allow the grippers to close on the belt, each of said keys arranged to open the grippers when the carriage reaches a predetermined point.
17. A machine of the character specified, 75 comprising a carrier having a series of detachable type-bars, printing mechanism arranged to receive any one of said type-bars, mechanism for transferring any one of said type-bars from the carrier to the printing mechanism 80 and back again, a belt positively driven first in one direction and then in the other, grippers connected to the carriers and adapted to close upon the belt to connect the carrier therewith, means for normally holding the grippers open, a series of compressible keys to operate the said means to allow the grippers to close on the belt, and each arranged to open the grippers when they have traveled with the belt a predetermined distance, said 85 keys being automatically held depressed by the said means, and devices carried by the said transferring mechanism for operating the said means to release the keys, when said transferring mechanism is returning the type-bar to the carrier.
18. A machine of the character specified, 90 comprising a carrier having a series of printing devices, controlling mechanism for arresting the carrier at a predetermined point, and automatic devices for moving said carrier to said predetermined point and then returning it to original position, said devices including a belt, means for temporarily connecting the belt and carrier, a shaft 95 operatively connected to said belt, and power devices for rotating said shaft first in one direction and then in the other direction.
19. A carrier for printing devices having 100 apertures consisting of a belt, and a series of spring-pins projecting therefrom to enter said apertures in said printing devices.
20. In a machine of the character described, a series of type-bars, a printing-cylinder adapted to receive any one of said bars, 110 and a carrier for said type-bars, said carrier and said cylinder having spring-pins adapted to be in alinement whereby the type-bars may be transferred from one to the other.
21. In a machine of the character described, printing mechanism, a series of printing devices, each adapted to be moved into printing position in said printing mechanism, an automatically-operated carrier adapted to present any one of the devices to the printing mechanism, and means for centering the carrier. 115
22. A ticket-printing machine comprising printing mechanism, a series of keys controlling said mechanism, and devices for holding each key depressed after it has been operated, until the ticket is printed, said devices comprising a projection on each key and a slotted tube with which said projection may engage. 125
23. A machine for printing tickets com- 130

prising printing mechanism having provisions for receiving a type-bar, said printing mechanism having ticket-numbering devices actuated by the type-bar.

5 24. A machine for printing tickets comprising a series of type-bars, provisions for moving any one of said type-bars in printing position, numbering-disks and means engaged by the type-bar whereby the disks are moved each time a type-bar is moved into printing position.

15 25. A machine of the character described, comprising an impression-cylinder, a coacting printing-cylinder provided with a socket to receive a type-bar, numbering-disks mounted on said printing-cylinder, and disk-actuating mechanism having a portion extending normally into the socket whereby the insertion of a type-bar into the socket operates the 20 disk-actuating mechanism.

25 26. A machine of the character described comprising printing-cylinders for printing the end of a strip of paper, means for severing the printed end, and means for automatically 25 withdrawing the strip after the severing of the end.

30 27. A machine of the character described, comprising printing mechanism, means for feeding a strip of paper thereto, means for severing the printed ticket from the end of the paper strip, and means for automatically withdrawing the strip after the severing of the end.

35 28. A machine of the character described, comprising printing mechanism, means for feeding a strip of paper thereto, means for severing the printed ticket from the end of the paper strip and a tension device for the said strip, constructed and arranged to partially withdraw it after the end thereof has been 40 severed.

45 29. A machine of the character described, comprising printing mechanism, means for feeding a strip of paper thereto, means for severing the printed ticket from the end of the paper strip, and a weight frictionally engaging the strip and adapted to be carried along therewith, said weight partially withdrawing the said strip when the end thereof has been severed.

50 30. A machine of the character described, comprising printing mechanism means for feeding a strip of paper thereto, means for severing the printed ticket from the end of the paper strip, a weight having means for frictionally engaging the paper strip whereby it is carried along with said strip, and stops for limiting the movement of the said weight, whereby when the strip is released by the feeding means, the weight withdraws it a pre-determined distance.

55 31. A machine of the character described comprising mechanism for printing and consecutively numbering tickets, recording means including numbering mechanism for 60 permanently recording the numbers of the

65 tickets, and a plurality of keys or selectors, each controlling the ticket printing and numbering mechanism, and the recording mechanism.

70 32. A machine of the character specified, comprising printing mechanism for the tickets, means for feeding the tickets means for supporting and feeding a record-sheet, and mechanism for automatically recording the total of sales of the tickets on said record-sheet. 75

80 33. A machine of the character specified, comprising ticket-printing mechanism, and means for severing each ticket means for supporting a record-sheet, and auditing or recording mechanism for recording the total of sales of the tickets on the record-sheet.

85 34. A machine of the character described, comprising devices for printing the names of different stations on a series of tickets, means for feeding the tickets means for feeding a record-sheet, and mechanism for indicating and classifying on said sheet the destinations on said tickets.

90 35. A machine of the character described, comprising devices for printing and numbering consecutively a series of tickets, means for feeding said tickets mechanism for feeding a record-sheet, mechanism for recording on the said sheet the destination printed on each ticket, mechanism for printing on said sheet the number of each ticket, and the summation of sales of the tickets, and mechanism for supplying power to the said parts. 95

100 36. A machine of the character described, comprising devices for printing and consecutively numbering a series of tickets, means for feeding said tickets means for feeding a record-sheet, mechanism for recording the destination of each ticket on the record-sheet, mechanism for recording the number 105 of each ticket on the record-sheet, and mechanism for recording the summation of sales of the tickets.

110 37. A machine of the character described, comprising devices for printing the names of different stations on a series of tickets, a series of manually-operated keys, one for each station for controlling the printing mechanism, means for feeding a record-sheet, and mechanism controlled by the said keys for 115 indicating on the record-sheet the name of each ticket, as it is printed.

120 38. A machine of the character described, comprising devices for printing the names of different stations on a series of tickets, a series of keys, one for each station, for controlling the printing mechanism, and means for making a permanent record of each ticket and the destination printed thereon.

125 39. A machine of the character described, comprising devices for printing the names of different stations on a series of tickets, a series of keys each controlling the printing mechanism, means for feeding a record-sheet, and a marking device for recording on the 130

sheet the printing of each ticket, said marking device being positioned by each of said keys.

40. A machine of the character described, comprising devices for printing the names of different stations on a series of tickets, means for feeding said tickets and auditing mechanism consisting of means for supporting a record-sheet having a space for each station and means for indicating the names of each station in its own space.

41. A machine of the character described, comprising means for feeding a record-sheet, a marking device movable over the said sheet, a means for causing the engagement of the marking device and the sheet and a series of keys, each arranged to arrest the marking device at a predetermined point, on said sheet.

42. A machine of the character described, comprising means for feeding a record-sheet, a marking device, means for automatically moving the marking device transversely of the said sheet, a series of keys each arranged to arrest the marking device at a predetermined point, and means for bringing the record-sheet and the marking device into engagement.

43. A machine of the character described, comprising means for feeding a record-sheet, a marking device, means for moving the marking device transversely of the record-sheet, a series of keys each arranged to arrest the marking device at a predetermined point relatively to the sheet, and a movable platen operated automatically to thrust the record-sheet against the marking device.

44. A machine of the character described, comprising means for feeding a record-sheet, numbering devices for the record-sheet, a marking device, means for moving the marking device transversely of the sheet, and a series of keys, each controlling the marking device and the numbering device.

45. A machine of the character described, comprising a series of printing devices, a carrier for said devices, power devices for moving said carrier, a series of keys each arranged to arrest the carrier at a predetermined point, means for feeding a record-sheet, and a marking device connected to said carrier and movable over the record-sheet.

46. Recording mechanism for a ticket-printing machine, comprising means for supporting a record-sheet, devices for printing the number of each ticket on said sheet, devices for adding and printing the total of sales of tickets on the said sheet, a marking device movable across the record-sheet for indicating the destination of each ticket, power devices for imparting movement to the said parts, and a series of keys each controlling all of the said devices.

47. A machine of the character described, comprising mechanism for printing the names of a series of different stations on a se-

ries of tickets, and automatically-operated mechanism controlled by the printing mechanism including means for supporting a record-sheet for recording the summation of sales of the tickets.

48. A machine of the character described, comprising mechanism for printing the names of a series of different stations on a series of tickets, means for feeding said tickets and automatic auditing mechanism including a record-sheet, and devices for adding and indicating on the record-sheet the summation of the sales of the tickets.

49. A machine of the character described, comprising mechanism for printing the names on a series of tickets, means for feeding said tickets a series of keys, each causing the printing of a particular name on a ticket, means for supporting a record-sheet, mechanism for indicating the summation of the sales of the tickets on the record-sheet.

50. A machine of the character described, comprising printing mechanism including a series of type-bars, each adapted to be moved into printing position, mechanism for causing any one of said bars to assume a printing position, means for supporting a record-sheet, and automatic mechanism controlled by said type-bars for making a record on said record-sheet of the prices of the tickets.

51. A machine of the character described, comprising printing mechanism including a series of interchangeable type-bars, a series of keys, one for each type-bar, for causing any particular one of said type-bars to assume a printing position, means for supporting a record-sheet, and automatic mechanism controlled by said type-bars and set in motion by said keys for recording the price of each ticket on the record-sheet.

52. A machine of the character described, comprising printing mechanism including a series of interchangeable type-bars, each formed to indicate the price of the ticket printed thereby, and automatic mechanism controlled by said type-bars for recording the price of each ticket printed.

53. A type-bar formed with a series of stops each indicative of a number from 0 to 9.

54. A machine of the character described, comprising a series of type-bars, each having a portion thereof formed to indicate the price of the ticket printed thereby, and auditing mechanism for recording the price of the ticket, said mechanism including adding devices controlled by the type-bars.

55. A machine of the character described, comprising printing mechanism, and auditing mechanism, said auditing mechanism including numeral-bearing disks, means for actuating said disks, and mechanism controlled by the printing mechanism for determining the degree of movement of said disks.

56. A machine of the character described,

comprising a series of type-bars, each having a portion thereof formed to indicate the price of the ticket printed thereby, adding devices comprising a series of numeral-bearing disks, 5 and means movable a predetermined distance to operate said disks, and hoods or shields controlled by said type-bars and adapted to be inserted between the disks and the said operating means, for limiting the degree of movement of the said disks.

57. A machine of the character described, comprising printing mechanism, means for feeding tickets thereto a series of keys controlling said printing mechanism, and auditing mechanism controlled by the printing mechanism and released by said keys.

58. A machine of the character described, comprising a series of printing devices and auditing mechanism, said auditing mechanism including a series of adding numeral-bearing disks, a ratchet operatively connected to each disk, a pawl for actuating each ratchet, a shield or hood adapted to be inserted between each pawl and its ratchet for determining the extent of movement of the ratchet, and automatic devices controlled by said printing devices for operating said hoods or shields.

59. A machine of the character described, comprising a series of printing devices, each having stops, and auditing mechanism including adding devices, and a series of automatically-operating fingers limited in movement by the said stops, for controlling the adding devices.

60. A machine of the character described, comprising a series of type-bars, each having stops on its end, printing mechanism adapted to receive any one of said type-bars, and auditing mechanism, said auditing mechanism including adding devices, means for actuating said devices, and a series of automatically-operating fingers each adapted to engage a stop on the operating type-bar to determine the movement of the adding devices.

61. A machine of the character described, comprising a series of type-bars each having stops on its end, printing mechanism adapted to receive any one of said type-bars, and auditing mechanism, said auditing mechanism including adding devices, means for actuating said devices, a series of automatically-operating fingers each adapted to engage a stop on the operating type-bar to determine the movement of the adding devices, mechanism for automatically releasing said fingers to engage said stops, and mechanism for automatically returning said fingers to inoperative position.

62. Auditing mechanism comprising a supporting-shaft, a series of cams rigid on said shaft, a series of numeral-disks loose on the shaft and alternated with said cams, said disks having teeth, and a pawl carried by 65 each of said disks and adapted to ride up on one of said cams to engage the teeth of the next succeeding disk.

63. Auditing mechanism comprising a supporting-shaft, a series of numeral-disks each 70 mounted on the shaft and provided with ratchet-teeth, and a yielding pawl to engage the teeth of the next adjacent disk, and stationarily-mounted arms or fingers to engage the pawls once during each revolution thereof to engage them with the next adjacent disk to impart a movement thereto.

64. A machine of the character described, comprising mechanism for printing a ticket, mechanism for making a record of the price 80 and destination of each ticket, power devices for operating the said mechanism, a governor for regulating the speed of said devices, a series of keys each controlling the printing and auditing mechanism and devices operated by 85 any one of the keys for releasing the power devices.

65. A machine of the character described, comprising mechanism for printing a ticket, mechanism for making a record of the price 90 and destination of each ticket, a weight raised manually for furnishing power to said mechanism, a stop for holding the mechanism against movement, and a series of keys each controlling the printing and auditing 95 mechanism, and each adapted to displace said stop.

66. A machine of the character described, comprising mechanism for printing the names of any one of a series of stations on a series of 100 tickets, a series of depressible keys controlling said printing mechanism, power devices, and mechanism for causing the printing mechanism to print the names of the same station on a series of tickets.

67. A machine of the character described comprising a plurality of ticket-printing type-bars, a similar number of keys for controlling the operation of said bars, and recording mechanism for recording each operation of 110 each bar.

In testimony whereof I have signed my name to this specification, in the presence of two subscribing witnesses, this 21st day of December, A. D. 1897.

FRANK J. WILLS.
